UNITED STATES PATENT OFFICE.

MATTHIAS H. REIMERS, OF HOBOKEN, NEW JERSEY, ASSIGNOR TO W. N. BEST CORP., OF NEW YORK, N. Y., A CORPORATION OF NEW JERSEY.

OIL BURNER.

Application filed December 20, 1923. Serial No. 681,686.

To all whom it may concern:

Be it known that I, MATTHIAS H. REIMERS, a citizen of the United States, and resident of Hoboken, in the county of Hudson and 5 State of New Jersey, have invented certain new and useful Improvements in Oil Burners, of which the following is a specification.

This invention is an atomizing device for 10 forming a spray or mist of liquid fuel by causing two jets or streams of the liquid fuel to flow through a passage in opposite directions to the outlet orifice where the two streams meet under pressure and emerge 15 to form the spray.

One of the main objects of my invention is to facilitate the cleaning of all of the passages and the reassembling of the parts in the proper adjustment.

20 A further object is to so design the parts that the passages through which the liquid flows to the outlet orifice may be opened for cleaning, or the parts having said passage are replaced by substitute parts to 25 produce a flame of different shape or size.

A further object is to provide a construction in which the liquid is delivered under pressure through the outlet orifice to form the mist or spray, or may be delivered 30 through said orifice by the action of steam, compressed air, or other motive fluid, and without necessitating any change in the liquid delivery passage or orifice presenting member.

35 In the accompanying drawings:

Fig. 1 is a side elevation of a burner constructed in accordance with my invention.

Fig. 2 is a top plan view.

40 Fig. 3 is a face view.

Figs. 4 and 5 are sections on the lines 4—4 and 5—5 respectively of Fig. 1, and

Fig. 6 is a section on the line 6—6 of Fig. 2.

45 My improved burner includes a head or body member 10 adapted to be connected in any suitable manner to a liquid fuel supply pipe 11. The head has a large central chamber within which is a surface presenting an annular groove which receives the liquid fuel at one point and delivers it through an outlet orifice at a diametrically opposite point. The fuel thus flows to the outlet orifice as two streams or jets from the same 50 source and in opposite directions, meeting

at the outlet orifice. The parts which form or present the said annular groove are so designed that when removed the groove is exposed throughout its entire length, and thus easily cleaned. In the specific construction illustrated there is provided an annular member or ring 12 which seats against a shoulder within the head, and has its outer cylindrical surface snugly fitting the peripheral wall of the chamber. The annular member 12 is held in place by a centrally disposed member or plug 13 which has a flange portion 14 seating against the face of the annular member 12, a plug portion 15 snugly fitting within the annular member 12, and a stem portion 16 projecting beyond the opposite side of the head to receive the clamping nut 17. By removing this nut the central member 13 and the annular member 12 may be removed from the head. 70

Two of the three members cooperate to form an annular groove. As shown this groove 18 is formed on the inner cylindrical face of the annular member 12, and the inner or open side of the groove is closed 80 by the peripheral surface of the plug portion 15.

The head 10 and annular member 12 have registering passages 19 leading from the supply pipe 11 to the groove 18 to form an inlet or supply passage to the groove. At a point diametrically opposite to this passage 19 the annular member is provided with an outlet orifice in the form of a slot 20 cut in the peripheral face and intersecting the groove. The head is so designed that this slot 20 opens directly into the air and forms the outlet orifice from the groove 18. As shown the head has a V-shaped groove 21 in the face thereof registering with the slot 20, and to permit the fuel to emerge from the slot 20 in the form of a substantially flat, fan-shaped mist. The mist or spraying effect is produced by the two streams flowing along the groove 18 in opposite directions from the passage 19 and meeting head on at a point directly opposite to the slot or outlet orifice 20. 90

It will be noted that by merely removing the nut 17 the members 12 and 13 may be removed and a new member 12 inserted with a larger or smaller groove, and with the desired shape and size of slot 20 or other outlet orifice in accordance with the shape and character of the flame to be pro- 100 105 110

duced. The removal of these parts exposes the inner side of the groove throughout its entire length, and permits it to be effectively cleaned when necessary.

5 In assembling the parts it is essential that the annular member 12 be in a definite and predetermined position, particularly so far as regards the slot 20 and the inlet passage 19. Any suitable registering means may be 10 employed, that shown being a pin 22 extending substantially parallel to the axis of the plug member 15 and intersecting the opposed faces of the exterior of the ring 12 and the interior of the chamber of the head. 15 This prevents any relative rotation of the three parts, and insures the assembling in a definite and predetermined position.

The construction as hereinbefore described is adapted for the forming of the spray of 20 liquid fuel by the impact of the two streams meeting at the outlet orifice. The construction is particularly adapted for use of steam, compressed air or atomizing fluid as the means for forming the spray. This may be 25 accomplished by providing the center member 13 with an axial passage or chamber 23 communicating at one end of the member with a supply pipe 24. The plug portion 15 of the central member has a passage 25 leading radially from the passage 23 to the periphery at a point directly opposite to the outlet orifice 20. Steam or compressed air may be delivered under high pressure through the pipe 24, and oil or other liquid 30 fuel under lower pressure through the pipe 11. The jet of atomizing fluid delivered from the passage 25 will spray the liquid fuel out through the orifice 20. If desired I may deliver the liquid fuel through the pipe 24 and the atomizing fluid through the pipe 11. In this case the steam or other atomizing medium would be under a comparatively low pressure, but perfect atomization 35 may be obtained.

40 Two sets of plug members may be provided, one with pipe connection 24 and jet passage 25, and the other without these features. Thus either type of construction may be manufactured with standardization of 45 the parts, and plugs of both types may if desired be supplied with each burner so that the user may produce either type of atomization.

In assembly or in use a ring member is 50 employed with the proper size of groove and the proper shape and size of outlet orifice and this may vary depending upon whether or not atomizing fluid is delivered through the central or plug member.

55 Having thus described my invention, what I claim as new and desire to secure by Letters Patent is:

1. A liquid fuel burner including a body portion having a liquid fuel supply passage 60 and an outlet orifice, and a removable annu-

lar member presenting an annular groove communicating with said passage, and said outlet, at diametrically opposite points and a second removable member closing the open side of the groove.

2. A liquid fuel burner including a body member having a supply passage, an outlet orifice and a central chamber, and a removable annular member within said chamber and presenting an annular groove communicating with said supply chamber and said outlet orifice and means extending through said annular member and retaining the same in position within the chamber.

3. A liquid fuel burner including a body member having a supply passage, an outlet orifice and a central chamber, an annular member within said chamber and presenting an internal annular groove communicating with said supply chamber and said outlet orifice, and means for detachably securing said annular member in position and closing the open side of said groove.

4. A liquid fuel burner including a body member having a central chamber and a supply passage, an annular member within said chamber and a plug member within said annular member for securing the latter in position, one of the coacting faces of one of said members presenting an annular groove having its open side closed by the other of said members and said burner having a supply passage and an outlet orifice communicating with said groove at diametrically opposite points.

5. A liquid fuel burner including a body member having a central chamber and a supply passage, an annular member within said chamber and a plug member within said annular member for securing the latter in position, said annular member having an annular groove upon its inner face and radial passages at diametrically opposite points, the open side of the groove being closed by the plug member, one of said passages serving as an outlet orifice and the other of said passages communicating with the supply passage of the body member.

6. A liquid fuel burner including a body member having a central chamber and a supply passage, an annular member within said chamber and a plug member within said annular member for securing the latter in position, the annular member having an annular groove communicating with said supply passage, and the burner having an outlet orifice communicating with the annular groove at a point diametrically opposite to said supply passage.

7. A liquid fuel burner including a body member having a central passage, an annular member seated within said passage, a plug member extending through said annular member and presenting a threaded

stem extending beyond the body member, and a nut on said stem for holding the three members together, said body member having a supply passage leading to the periphery of the annular member, the annular member having an annular groove communicating with said supply passage, and said burner having an outlet orifice communicating with the groove at a point diametrically opposite to the supply passage.

8. A liquid fuel burner including a body member having a supply passage and an outlet orifice, an annular member within said body member and having an annular groove forming two paths for the liquid fuel from the supply passage to the outlet orifice and a central plug member closing the open side of the groove and having a supply passage disposed radially thereof and in alignment with the outlet orifice.

9. A liquid fuel burner including an outer member, an inner member, and an intermediate member, one of the two last mentioned members being formed with an annular groove in the surface toward the other of the last mentioned members, registering ports in the outer and intermediate members communicating with the groove, and

means for securing together the outer and inner members and retaining the intermediate member in position.

10. A liquid fuel burner including a body member, an annular member disposed therein, and a plug member within said annular member, said plug member having a supply passage extending radially from the center to the periphery, said annular member having an annular groove upon the inner surface thereof, and an outlet orifice opposite to the first mentioned supply passage, and the body member having a supply passage communicating with the annular groove at a point diametrically opposite to the outlet orifice.

11. A device of the character defined in claim 10 in which the plug member is provided with a threaded stem for securing it and the annular member to the body member.

12. A construction as defined in claim 10, in which means are provided for preventing relative rotation of the three members.

Signed at New York city, in the county of New York and State of New York, this 14th day of December, A. D. 1923.

MATTHIAS H. REIMERS.
